PIPE HOLDING VISE

Philip B. Wallace, San Francisco, Calif., assignor
to U. S. Pipe Bending Co., San Francisco, Calif.,
a partnership of California

Application September 2, 1941, Serial No. 409,209

5 Claims. (Cl. 81—26)

My present invention relates to a pipe holding device, and more particularly to a vise for holding the end of a pipe upon a pipe bending machine of the type illustrated in my prior Patent No. 1,473,893 on Bending machine, issued jointly to me and Frank H. Fox.

An object of the invention is to provide a vise for holding pipe and other objects in which the gripping action of the vise is accomplished in a simple, efficient and novel manner.

Another object of the invention is to provide a pipe holding vise for bending machines in which the pipe gripping and releasing operation of the vise is accomplished by lever means of novel construction.

Another object of the invention is to provide a new and effective means for gripping large pipes and other objects in a simple and convenient manner with a minimum of separation of the gripping elements of the vise.

Other objects and advantages of the invention will be in part evident to those skilled in the art and in part pointed out hereinafter in the following description taken in connection with the accompanying drawing, wherein there is shown by way of illustration and not of limitation preferred embodiments thereof.

In the drawing:

Figure 1 is a perspective view of one form of the invention,

Figure 2 is a vertical sectional view taken longitudinally through the device illustrated in Figure 1,

Figures 3 and 4 are perspective views showing details of the device as illustrated in Figures 1 and 2,

Figures 5 and 6 are respectively a side elevation and plan view with parts broken away to illustrate details of construction,

Figure 7 is a fragmentary side elevation partly in section showing a modification of the invention, and

Figure 8 is a perspective view showing a detail of the construction used in the device as illustrated in Figure 7.

While my invention may find many fields of application, I have, for the purpose of illustration, shown it as mounted upon the frame or stationary portion of a pipe bending machine, such as is illustrated in the aforesaid patent. As here shown, the vise comprises a body member 10 that is slidably mounted upon a supporting frame 11 which, as above suggested, forms a part of a pipe bending machine. The body member 10 has an upstanding integral jaw

forming portion 12 and cooperating with this jaw forming portion 12 there is an outwardly disposed jaw forming portion 13 which is movable relative to the body member 10. The outwardly disposed jaw forming portion 13 has a threaded portion 14 which extends adjacent and under the body member 10 where it carries an abutment forming member 15 that is adjustable therealong by means of a threaded nut 16. The abutment forming member 15 is here shown as in the form of an inverted channel-like member so that it may be conveniently removed and replaced by similar members of different lengths, as the work requires. As an alternative, it is 5 also contemplated that the abutment forming member 15 may be in the form of a cylindrical sleeve which may entirely surround the threaded portion 14. The body member 10 is shown as provided with a walled aperture 17, and extending transversely through this walled aperture 17 of the body member 10 there is a shaft 18 which, as is more clearly shown in Figure 2, has an eccentric portion 19 that is located within the walled aperture 17. The shaft 18 carries an 10 operating lever 20 and upon the eccentric portion 19 of the transversely extending shaft 18 there is a novel lever forming member 21. As shown in Figure 4 of the drawing, the lever forming member 21 is bifurcated or forked at its lower 15 end so as to provide a pair of downwardly extending ears 22 which straddle the threaded portion 14 of the movable jaw forming member 13. These ears 22 are extended outwardly slightly and rounded off so as to engage the inner end 20 of the adjustable abutment forming member 15, and at its upper end the lever forming member 21 carries an upwardly and outwardly extending lip 23. This lip 23 upon the lever forming member 21 is adapted to engage an inwardly inclined bearing surface 24 that is formed upon the rearward wall of the aperture 17 formed in the body member 10 and, as a result, when the transversely extending shaft 18 is rotated, the lever forming member 21 will be first operated as a 25 lever of the third-class with its fulcrum upon the inclined surface 24. This will cause the outwardly disposed jaw member 13 to move inwardly toward the integral jaw forming portion 12 of the body member 10. Then, after the eccentric 30 portion 19 upon the shaft 18 has passed its extreme off-center position, further rotation of the transversely extending shaft 18 will cause the lever forming member 21 to be carried downwardly and, as a result of the inclined character 35 of the surface 24 upon the rear wall of the

aperture 17 and the outwardly extending lip 23, it will operate as a wedge to exert a further vise tightening effort against the abutment 15. Under these conditions, with suitably formed pipe engaging blocks 25 and 26 between the jaw forming members 12 and 13 of the vise, it will be possible to clamp a length of pipe 27 in such a manner that it will be held firmly against rotation and/or axial displacement. At the same time, due to the wedge-like action of the lever forming member 21, the vise will be held in this condition without any danger of a loosening thereof by any stresses placed upon the pipe 27, as during a bending thereof.

As will be more clearly seen from an inspection of Figures 3 and 4 of the drawing, the transversely extending shaft 18 and the lever forming member 21 are adapted to be mounted in and held in cooperating relation with the body member 10 without any securing means other than that which is provided by the operating lever 20 that extends through a hole 28 formed in the projecting end of the shaft 18. In its preferred form, the shaft 18 has an enlarged end 29 that is concentric to the smaller portion of the shaft, and the eccentric portion 19 is formed intermediate these portions with an eccentricity that is equal to one-half the difference in the diameters of these two portions of the shaft. With this arrangement it will be seen that the shaft 18 can be projected through the body member 10 from the rear side thereof and through the lever forming member 21 when the latter is positioned in the walled aperture 17 and finally secured in place by the insertion of the operating lever 20 through the hole 28 at the projecting end of the shaft 18. As shown in Figure 4 of the drawing, the lever forming member 21 has a width corresponding to the axial length of the eccentric portion 19 formed, as above described, upon the transversely extending shaft 18.

While I have illustrated and described an embodiment of my invention in which the movable jaw forming portion of my device is formed as a single unit, it is to be understood that the invention may take many other forms. For example, as illustrated in Figures 5 and 6 of the drawing, instead of the movable jaw forming member 13, I may provide a movable jaw supporting member 30 having a threaded inwardly extending portion 31 that corresponds to the threaded portion 14 hereinabove referred to. Like the threaded portion 14, the movable jaw supporting member 30 of this embodiment will carry an abutment forming sleeve which will cooperate with the lever forming member 21 carried by the transversely extending shaft 18 journaled upon the body member 10 in a manner similar to that described above. As here shown, the movable jaw supporting member 30 has an opening 32 into which a projecting end 33 of a rocker-bar 34 is extended. At its upper end the rocker-bar 34 has a similar projecting end 35 that extends into an opening 36 formed in the outer end of a tie-bar 37. At its other end the tie-bar 37 is threaded to receive an adjustable nut 38 that engages two spaced ears 39 formed upon the body member 10. As here illustrated, the openings 32 and 36 formed respectively in the movable jaw supporting member 30 and the tie-bar 37 are of a diameter slightly larger than the extending ends 33 and 35 of the rocker-bar 34. In its preferred form, this rocker-bar 34 has a curved surface which will permit it to rock over

the outer surface of the pipe engaging block 25 when it is drawn into final clamping engagement therewith, as when the lever 20 is operated to tighten the vise. This embodiment of my invention is particularly adapted for use with heavy objects, such as pipe of large diameter. An advantage of this arrangement is that it provides a vise with which extremely high pressures can be exerted without subjecting the clamping jaws to any bending stress, such as might be the case with a movable jaw 13 of the character shown in Figure 1 of the drawing. This arrangement has the further advantage that it can be easily released and disassembled so as to facilitate a placing of the large objects or heavy pipe therein. When constructed in this manner, it will be seen that with the lever forming member 21 released, the lower end of the rocker-bar 34 may be moved outwardly from the clamping block 25 and, at the same time, the tie-bar 37 may be taken off to permit the insertion of the pipe 27 therein. After the pipe 27 is placed in the vise and the rocker-bar 34 with its tie-bar 37 is positioned over the pipe 27, as here shown, the adjustable nut 38 will be turned up by hand until the clamping blocks 25 and 26 are brought into engagement with the cylindrical surface of the pipe 27. Then, by an operation of the lever 20, it will be possible to draw the movable jaw supporting member 30 inwardly and thus effect a final and secure clamping of the pipe 27.

In the embodiment of my invention illustrating Figure 7 of the drawing, I have dispensed with the outer pressure block 25 and have substituted therefor a pipe encircling means that may take the form of a cable, a steel strap, or a chain 40 which, as here shown, is connected at its lower end to a movable jaw supporting member 41. At its upper end the chain 40 has a threaded extension 42 which carries a nut 43 that is adapted to engage with the ears 39 upon the body member 10. In this arrangement, the movable jaw supporting member 41, like the jaw supporting member 30, carries an extending threaded portion 44 upon which the adjustable abutment 15 is adapted to be positioned in cooperating relation with the lever forming member 21, as above described. Formed in its upper surface, this movable jaw supporting member 41 also has an undercut or T-slot 45 into which the projecting ends of a pin 46 carried at the lower end of the chain 40 are adapted to be secured. The T-slot 45 is shown in Figure 8 of the drawing as terminating at a point 47 corresponding to that of the hole 32 formed in the movable jaw supporting member 30 previously described and, therefore, if the vise is equipped with a movable jaw supporting member 41 of this type, it will be possible to use the rocker-bar 34 and its tie-bar 37 interchangeably with the chain 40. In operation, when the vise is provided with the chain 40, as here shown, it will be seen that after the lever 20 has been operated to release the lever forming member 21, all tension will be removed from the chain 40 and, as a result, the threaded extension 42 with the nut 43 can be lifted free of the ears 39 upon the body member 10 to thus permit the removal of the pipe 27.

While I have, for the sake of clearness and in order to disclose the invention so that the same can be readily understood, described and illustrated specific devices and arrangements, I desire to have it understood that all such changes as come within the scope of the claims are to be considered as part of this invention.

Having thus described my invention, what I claim and desire to secure by Letters Patent is:

1. In a vise of the character described, the combination of a body member having a stationary jaw portion and a walled aperture extending vertically therethrough at the rear of said jaw portion, a movable jaw forming member having a threaded portion extending through said body member and beyond said walled aperture, an adjustable sleeve mounted upon the threaded portion of said movable jaw forming member, a shaft extending through said body member and having an eccentric portion disposed within the walled aperture of said body member, a lever forming member pivotally mounted upon the eccentric portion of said shaft engageable at one end with a wall of said walled aperture and engageable at its other end with said adjustable sleeve, and means for rotating said shaft, whereby said lever forming member will have a sliding fulcrum at its point of engagement with the wall of said aperture to exert pressure upon said adjustable sleeve and cause said jaws to move into clamping relation with each other.

2. In a vise of the character described, the combination of a body member having an integral jaw portion and a walled aperture extending vertically therethrough at the rear of said jaw portion, a movable jaw forming member having a threaded portion extending through said body member and beyond said walled aperture, an abutment carried by the threaded portion of said movable jaw forming member, a shaft extending transversely through said body member and having an eccentric portion disposed within the walled aperture of said body member, a lever forming member pivotally mounted upon the eccentric portion of said shaft engageable at its upper end with the rear wall of said walled aperture and engageable at its lower end with the abutment carried by the threaded extension portion of said movable jaw member, and means for rotating said transversely extending shaft, whereby said lever forming member will operate as a lever of the third-class with a sliding fulcrum to exert pressure upon said abutment and cause said jaws to move into clamping relation with each other.

3. In a vise of the character described, the combination of a body member having a jaw portion and a walled aperture extending therethrough at the rear of said jaw portion, a movable jaw supporting member having a threaded portion extending through said body member and beyond said walled aperture, an adjustable abutment mounted upon the threaded portion of said movable jaw supporting member, a shaft extending transversely through said body member and having an eccentric portion disposed within the walled aperture of said body member, a lever forming member pivotally mounted upon

the eccentric portion of said shaft engageable at one end with the rearward wall of said walled aperture and engageable at its other end with the adjustable abutment upon the threaded portion of said movable jaw supporting member, the rearward wall of said walled aperture being inclined toward the axis of said shaft, and means for rotating said transversely extending shaft, whereby said lever forming member will operate with a combined lever and wedge-like action to exert pressure upon said abutment and move said movable jaw supporting member relative to said body member.

4. An operating means for a pipe clamping device of the character described, comprising a stationary and movable pipe engaging means, a threaded means carried by said movable pipe engaging means and extending adjacent said stationary means, a shaft journaled upon said stationary pipe engaging means having an eccentric crank-like portion, a lever mounted upon the eccentric crank-like portion of said shaft and having a forked end disposed in straddling relation with said threaded means and an oppositely extending offset end, means carried by said stationary pipe engaging means forming a fulcrum with which the offset end of said lever slidably engages, an abutment upon said threaded means against which the forked ends of said lever engage, and means for turning said shaft, whereby said lever will be moved with a combined lever and wedge-like action to exert pressure upon said abutment and cause said movable pipe engaging means to move into clamping relation with said stationary pipe engaging means.

5. An operating means for a pipe clamping device of the character described, comprising a stationary and movable pipe engaging means, a threaded means carried by said movable pipe engaging means extending under said stationary means, a transversely extending shaft journaled upon said stationary pipe engaging means and having an eccentric crank-like portion, a floating lever mounted upon the eccentric crank-like portion of said shaft having a forked lower end disposed in straddling relation with said threaded means and a rearwardly extending upper end, means upon said stationary pipe engaging means forming an inclined surface with which the upper end of said floating lever engages, an abutment forming sleeve adjustably secured upon said threaded means against which the forked ends of said floating lever engage, and means for rotating said transversely extending shaft, whereby said floating lever will operate with a combined lever and wedge-like action to exert pressure upon said abutment and cause said movable pipe engaging means to move toward said stationary pipe engaging means.

PHILIP B. WALLACE.
